(57) **CLAIM**

The ornamental design for a decorative stand for a shot glass in the shape of a crocodile head, as shown.

DESCRIPTION

FIG. 1 is a perspective view of the decorative stand for a shot glass in the shape of a crocodile head showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken line showing of an actual shot glass is included for the purpose of illustration and forms no part of the claimed design.
